UNITED STATES PATENT OFFICE.

WILLIAM C. DEVEREAUX, OF DETROIT, MICHIGAN.

DOOR LATCH.

Application filed December 8, 1924. Serial No. 754,884.

This invention relates generally to door locks and latches and refers more particularly to those designed for use upon the doors of vehicle bodies.

5 One of the essential objects of the invention is to provide a lock of this type in which the bolt is adapted to be retracted by a novel form of roll back that is provided with a rounded end portion for engagement with 10 the bearing face of the bolt extension so that the retraction of the bolt from the outside of the vehicle is smoother and easier.

Another object is to provide a pivotal dog that is adapted to render the roll back 15 inoperative by engaging the same to one side of the bolt extension and that may be disengaged from the roll back to permit operation thereof without extending above the upper edge of the case plate.

20 A further object is to provide the dog with an extension that is adapted to engage the projection on the case plate for limiting the movement of the dog in one direction.

25 Still another object is to provide a strong and durable lock that is simple and compact in construction and can be manufactured at a comparatively low cost.

30 With the above and other objects in view the invention consists in certain novel features of construction, combinations and arrangements of parts as will be more fully described and particularly pointed out in the appended claims.

In the accompanying drawing;

35 Figure 1 is a side elevation of a door lock embodying my invention.

Figure 2 is a sectional view taken on the line 2—2 of Figure 1.

40 Figure 3 is a sectional view taken on the line 3—3 of Figure 1.

Figure 4 is a section on the line 4—4 of Figure 1.

Heretofore, locks have been provided in which the roll backs operable from the outside for retracting the bolt have been extended above the usual bolt extensions so that they may be engaged above the bolt extensions by suitable dogs for preventing retraction of the bolt from the outside of the vehicle. However it has been found that such extended roll backs did not provide mechanically efficient bearings against the bearing faces of the bolt extension and that as a result, the outside operating means of the lock worked hard when retracting the bolt. Moreover, such constructions are ob-

jectionable because the dogs used to render the roll backs inoperative usually extended above the upper edges of the case plates when in inoperative position.

With the present invention the objectionable features just referred to are overcome entirely, and I preferably provide a lock in which the roll back is preferably provided with a lateral projection that is adapted to 65 be engaged by the dog when lowered to render the roll back inoperative. Thus, the free end of the roll back may be rounded for engagement with the bearing faces of the bolt extensions so that the retraction of the 70 bolt from the outside of the vehicle will be much smoother and easier. Moreover, the arrangement is such that the dog may be pivoted lower on the case plate so that it is not necessary for the vehicle body builder 75 to perform as many operations on the door frame as previously required because the dog in the unlocked or inoperative position, does not extend above the case plate, as it did in the old style locks described above.

Referring now to the drawing in which like characters of reference designate corresponding parts throughout the several views, the numeral 1 designates a lock embodying my invention having a case plate 2 85 that is preferably secured to the inner side of a door and is provided at one edge with a laterally extending flange 4 that is secured to the outer edge of the door. Slidably mounted on the case plate 2 is a bolt 5 preferably 90 having a shank 6 and an enlarged head 7.

As shown, the head 7 preferably extends through a suitable opening 8 in the lateral flange 4 of the case plate and is adapted to engage a suitable keeper (not shown) upon 95 the door jamb of the vehicle body, while the shank 6 preferably extends between spaced guide lugs 9 preferably struck out from the case plate 2 and is provided at spaced points throughout its length with an upstanding extension 10 and a lateral projection or tongue 11. As shown, this shank 6 is preferably flat so that it may move behind a suitable cover plate 12 secured to the case plate 2, while any suitable means such as the helical spring 13 anchored preferably on the case plate 2 may be engaged with the rear end of the shank 6 to normally hold the bolt in projected position.

For retracting the bolt against the tension 110 of the spring 13 I preferably provide a suitable roll back 14 that is adapted to be oper-

- ated from the outside of the door, and a rotatable spindle 15 that is adapted to be operated from the inside of the door. As shown, the roll back 14 is engageable with 5 the forward extension 10 of the bolt shank 6 and is provided with a hub 16 that is journaled in aligned openings 17 and 18 respectively in the case plate 2 and cover plate 12, preferably immediately in rear of the 10 lateral flange 4. Any suitable means (not shown) may be engaged with the square opening 19 in the hub 16 for rocking the roll back against the extension 10 to retract the bolt.
- 15 The rotary spindle 15 is preferably journaled on the case plate 2 between spaced struck out bearings 20 and is prevented from moving vertically thereon by a ring 21 that is secured to the spindle 15, preferably at 20 the lower end thereof, and extends through aligned elongated openings 22 and 23 respectively in the case plate 2 and cover plate 12. As shown, this spindle 15 is preferably provided intermediate its ends with a suitable crank portion 24 that engages the lateral projection 11 of the bolt shank 6. Thus, with this construction, the roll back 14 may be moved to the rear against the extension 10 to retract the bolt without affecting the 25 spindle 15, and the latter may in turn be rotated so that the crank portion 24 engaging the shank projection 11 will retract the bolt without affecting the roll back 14. The spring 13 will always exert a pressure 30 through the lateral projection 11 of the bolt shank against the crank portion 24 of the spindle 15. However, a supplemental coil spring 25 is preferably provided at the upper edge of the case plate 2 to prevent any objectionable play of the spindle 15 and to 35 take care of any rattling thereof in the bearings 20. As shown, this spring 25 is preferably coiled about the spindle 15 and is terminally secured to the spindle and case 40 plate 2, so that the spindle will always be held snugly in the bearings 20. In order that the outside operating means may be rendered inoperative from the inside of the vehicle, I preferably provide a dog 26 that 45 is pivoted on the case plate 2 between the roll back 14 and spindle 15 and is adapted to prevent the roll back from moving to the rear to retract the bolt. As shown, this dog 26 is preferably rigidly secured to a short 50 horizontal spindle 27 extending through the case plate 2 and is adapted to be actuated by a suitable handle 28 nonrotatably secured to the spindle.
- 55 In order that the dog 26 may be raised or lowered without projecting above the upper edge of the case plate 2, the dog is preferably provided with an off-set portion 29 that projects forwardly at one side of the extension 10 and is adapted to engage a lateral extension or projection 30 of the roll back 60 14. This dog is also preferably provided in rear of the horizontal spindle 27 with a short extension 31 that is engageable with one of the bearings 20. Thus, the movement of the dog 26 is entirely independent of the 70 movement of the roll back 14 and vertical spindle 15. Moreover, when the dog 26 is in operative position behind the lateral extension 30 of the roll back 14, the vertical spindle 15 may be readily operated from the inside of the vehicle to retract the bolt. Furthermore the extension 31 cooperates with the adjacent bearing 20 to limit the upward 75 swinging movement of the dog 26. inasmuch as the dog 26 is movable to one side of the shank extension 10 and is engageable with the lateral extension 30 of the roll back, the free end of the latter may be used to bear against the bearing face 34 of the shank extension 10. In order that the retraction of the bolt from the outside of the door will be smooth, the free end of the roll back 14 is preferably rounded as shown at 80 35 for engagement with the bearing face 34 of the shank extension 10. 85
- 90 While it is believed that from the foregoing description the nature and advantages of the invention will be readily apparent, I desire to have it understood that I do not limit myself to what is herein shown and described, and that such changes may be resorted to when desired as fall within the scope of what is claimed.
- 95 What I claim as my invention is:
1. In a door lock, the combination with a 100 case plate, a cover plate therefor, and a locking bolt having an extension movable between said plates, of means for retracting the bolt including a roll back having an end portion engageable with the extension, said roll back having a lateral projection, and means 105 for dogging the roll back including a member pivoted on one of said plates engageable with said lateral projection.
2. In a door lock, the combination with a 110 case plate, and a locking bolt carried thereby having an extension, of means for retracting the bolt, including a roll back having a rounded end portion engageable with the extension and having a lateral projection, of 115 means for rendering the roll back inoperative including a dog pivoted on the case plate having an off-set portion adapted to engage the lateral projection of the roll back.
3. In a door lock, the combination with a 120 locking bolt having an extension, of means for retracting the bolt including a roll back engageable with the extension, and means for rendering the roll back inoperative including a member engageable with a portion 125 of the roll back at one side of the bolt extension.
4. In a door lock, the combination with a case plate, and a locking bolt movable on the case plate having an extension, of means for 130

- retracting the bolt including a roll back engageable with the extension, and means for dogging the roll back including a member mounted on the case plate having an off-set 5 portion adapted to move beside the bolt extension and engage directly with a portion of the roll back.
5. In a door lock, the combination with a locking bolt having an extension, of means 10 for retracting the bolt including a roll back engageable with the extension having a lateral projection, and means engageable with said projection for dogging said roll back.
6. In a door lock, the combination with a 15 case plate and a locking bolt carried by the case plate having an extension, means for retracting the bolt including a roll back engageable with the extension having a lateral projection, and a member mounted on the 20 case plate engageable with the lateral projection aforesaid for rendering the roll back inoperative.
7. In a door lock, the combination with a case plate having spaced bearings thereon,
- and a locking bolt carried by the case plate 25 having an extension and a lateral projection, of means for retracting the bolt including a roll back engageable with the extension, and a rotary spindle engaging the bearings on the case plate and having a portion engageable with the lateral projection, means for rendering the roll back inoperative including a member mounted on the case plate engageable with a portion of the roll back, and means for limiting the movement of said 30 member in one direction including an extension of the member engageable with one of the bearings aforesaid.
8. In a door lock, the combination with a locking bolt having an extension, of means 35 for retracting the bolt including a rollback engageable with said extension, and means for rendering the rollback inoperative including a pivoted element having a portion constituting an abutment for the rollback 40 movable beside said extension.

In testimony whereof I affix my signature.
WILLIAM C. DEVEREAUX.
